Attorney, Agent, or Firm—John H. Crowe

[21] Appl. No.: 948,750

[57] CLAIM

The ornamental design for a deck of playing cards, substantially as shown and described.

[22] Filed: Oct. 5, 1978

DESCRIPTION

[51] Int. Cl. .... D21—01

FIGS. 1 through 52 are front views of separate cards making up a deck of playing cards showing my new design.

[52] U.S. Cl. D21/43; D21/47

FIG. 53 is a view of the back of one of the cards, the back view of each of the other cards being a duplicate thereof.
